A. J. PURVIANCE, OF MOUNT ZION, IOWA, ASSIGNOR TO HIMSELF AND
J. A. MOSS, OF THE SAME PLACE.

Letters Patent No. 66,388, dated July 2, 1867.

IMPROVEMENT IN BALING-PRESS.

The Schedule referred to in these Letters Patent and making part of the same.

TO ALL WHOM IT MAY CONCERN:

Be it known that I, A. J. PURVIANCE, of Mount Zion, Van Buren county, State of Iowa, have invented a new and improved Baling-Press; and I do hereby declare that the following is a full, clear, and exact description thereof, which will enable others skilled in the art to make and use the same, reference being had to the accompanying drawing, forming part of this specification, in which—

Figure 1, Sheet No. 1, is an elevation of the press on the side opposite the power.

Figure 2 is a view of the under side of the press.

Figure 3, Sheet No. 2, is a central vertical section.

Similar letters of reference indicate like parts.

The nature of this invention consists in combining gearing with windlass and shackle-rigging power for compressing and baling hay or cotton, the object of the combination of these two means of pressing in one machine being rapidity and dispatch of the principal part of the work by the gearing movement and powerful compressing upon the bale by means of the slower action of the windlass and shackle arrangement exerted by the same driving force when the final compression is applied to make a bale very compact and of the least possible bulk. The machine is made strong and portable, and any horse-power or other driving apparatus may be attached to work it.

A is a rectangular frame, constructed of heavy hard-wood timbers fastened with bolts or in any suitable manner. At one end of the frame is a box or trunk, B, figs. 2 and 3, on the inside for receiving the hay or cotton and forming the bale, which stands on end when packed. The head-block *a*, fig. 3, at one end of the trunk B, is stationary, opposite to which is the follower or plunger *b*, operated by rack-beam C, on the upper side of which is a straight rack, *c*, worked by a sliding pinion, *d*, connected with the gearing, to be described, and also by a windlass and shackle-ropes over pulleys and rollers, these two methods of operation being applied separately and independently of each other, as may be desired. The gearing arrangement has a driving-shaft, D, figs. 2 and 3, at the bottom of the press, which lies across the press and has its bearings on the bottom frame timber. Horse or other power is attached at one end of the driving-shaft D on one side of the press, fig. 2, and on the other end is a pinion, *e*, fig. 1, which works into a spur-wheel, *f*; on the shaft of the spur *f* on the opposite side of the press is another pinion, *g*, figs. 2 and 3, which drives two spurs *h* and *i*, shown in all the figures. The spur *h* is on a shaft which revolves a windlass, E, hung on a swinging-frame, R, at the back end of the press-frame A, and is under the rack-beam C. The windlass E has a rope, *k*, attached, which runs from it to one of three guide-pulleys on one shaft F, fig. 3, set in a loose block, G, between and across the framing-timbers A; thence the rope *k* passes to one of two pulleys *z z*, in a loose adjustable frame, H, at the extreme back end of the rack-beam C; thence back to the middle of the three guide-pulleys on F hung in the block G; thence to the other pulley *z* in the frame H; thence to the third pulley on F in the block G; and thence to a hook-and-eye coupling or makefast, *l*, figs. 1 and 3, at the back end of the rack-beam C. The rack-beam C is a frame of three long timbers, on the middle one of which is the rack *c*. This frame rests and travels on two rollers *II'*, figs. 2 and 3, that lie across the machine. The spur *i* is on a sliding-shaft, P, which is shifted as required by a hand-lever, *m*, which is hung in a frame on the opposite side of the machine. On the shaft I, close to the lever *m*, is a fast-pinion, *p*, which shifts by moving the shaft in and out of gear with the spur *f*, and in the middle of the same shaft is a sliding-pinion, *q*, connected with which is a hand-lever, *n*, fig. 3, for shifting it in and out of gear with the rack *c*. On the top of the press is a door, K, fig. 3, hung on hinges for opening to fill the trunk B with hay or cotton, and closing to from the upper side of the trunk B when the bale is compressed. On both sides of the trunk B, next to the head-block *a*, are strong doors, L, fig. 1, secured by bars and hooks which form the sides of the trunk where the bale is compressed and fastened, and when the bale is pressed are opened to secure the wires or ropes and let it out of the trunk. At the end, on one side, a frame, M, is hung to swing back and forth, upon which is set upon an upright spindle, *w*, a spool, *s*, for carrying the rope or wire *y*, and moving up and down when used for baling. The spindle is turned by a crank, *v*, at the top. The under side of the trunk B is formed of a hinged bottom, N, fig. 2, the front or rising end of which rests on an eccentric roller, O, figs. 2 and 3, lying across the frame A, by which it is raised by a crank at one end of the eccentric roller when the hay or cotton is being compressed, and lowered when the bale is fastened for the purpose of relieving the ends

of the bale and allowing it to come out of the trunk easily. In the inside of the head-block *a* and follower *b* are ordinary recesses or grooves *t t*, for receiving the ropes or wires which go around and secure the bale.

The machine is operated as follows: The doors *L L* on the sides are closed; the door *K* on the top is opened for filling in the hay or cotton into the trunk *B*; the windlass rigging is unshipped by releasing the rope *k* from the coupling *l*, taking the pins *o o* out of the clamps *u u* which support the adjustable frame *H*. The spur *h* is also thrown out of gear with the driving-pinion *g* by moving out the frame *R* on which the windlass *E* and the spur *h* are both hung. By means of the hand-lever *m*, the fast-pinion *p* is put in gear with the spur *f*, and the spur *i* in gear with the pinion *g*; the hand-lever *n* then throws the shifting-pinion *d* in gear with the rack *c*. The driving power being applied, the rack-beam *C* bears the follower *b* against the cotton or hay in the trunk *B* until it is nearly compact enough. The windlass rigging is then adjusted again and the bale compressed as hard as required with the same power by the more powerful action of the windlass.

Having described the construction and operation of my improved baling-press, what I claim as new, and desire to secure by Letters Patent, is—

1. The combination and arrangement of the shifting-pinion *d*, rack-beam *C*, spur-wheel *i*, pinions *e g p*, sliding-shaft *P*, spur-wheel *f*, windlass *E*, swinging-frame *R*, shaft *F*, loose block *G*, ropes *h i k*, pulleys *z z*, roller *II'*, constructed and operating in the manner as and for the purpose specified.

2. I claim the windlass *E*, in combination with the guide-pulleys in the block *G*, the rope *r*, the adjustable frame *H*, and the rack-beam *C*, arranged and applied to compress the bale substantially in the manner herein described.

3. I claim the shifting-levers *m* and *n*, in combination with the shifting-shaft *P*, the shifting-pinion *d*, and the rack *c*, constructed and applied substantially as and for the purposes herein set forth.

A. J. PURVIANCE.
